[57] CLAIM

The ornamental design for a combined retroreflector and delineator for roadways, as shown and described.

DESCRIPTION

FIG. 1 is a top plan view of a combined retroreflector and delineator for roadways showing my new design;

FIG. 2 is a bottom plan view thereof;

FIG. 3 is a left side elevational view thereof;

FIG. 4 is a rear elevational view thereof;

FIG. 5 is a right side elevational view thereof;

FIG. 6 is a front elevational view thereof;

FIG. 7 is a perspective view thereof;

FIG. 8 is an enlarged sectional view taken along line 8—8 of FIG. 5; and,

FIG. 9 is an enlarged sectional view taken along line 9—9 in FIG. 6.

FIG. 1

FIG. 2

FIG. 3

FIG. 4

FIG. 5

FIG. 6

FIG. 7

FIG. 8

FIG. 9
